UNITED STATES PATENT OFFICE.

MORRIS WISE, OF NEW YORK, N. Y., ASSIGNOR TO HIMSELF, AND THOMAS KNIGHT, OF BROOKLYN, NEW YORK, AND E. T. FELLOWS, OF ENGLEWOOD, NEW JERSEY.

MANUFACTURE OF BOOTS OR SHOES.

SPECIFICATION forming part of Letters Patent No. 366,142, dated July 5, 1887.

Application filed May 5, 1887. Serial No. 237,237. (No model.)

To all whom it may concern:

Be it known that I, MORRIS WISE, a citizen of the United States, residing at New York, in the county and State of New York, have 5 invented new and useful Improvements in the Manufacture of Boots or Shoes, of which the following is a specification.

This invention relates to an improvement in the manufacture of boots or shoes, as fully 10 explained in the following specification and claims and illustrated in the accompanying drawings, in which—

Figure 1 represents a perspective view of my improved shank-spring. Fig. 2 is an inverted plan of a boot during the process of 15 lasting. Fig. 3 is a similar view after the lasting has been completed. Fig. 4 is a longitudinal vertical section of a boot when finished. Fig. 5 is a transverse vertical section in the 20 plane $\alpha\alpha$, Fig. 4.

Similar letters indicate corresponding parts.

In the drawings, the letter A designates a shank-spring, which is made of sheet steel or of any other material suitable for the purpose, 25 and which is provided with a series of holes, a, and with a series of spikes, b, firmly connected to the shank-spring.

B is the upper of a boot or shoe, and the shank portion of this upper is provided with 30 flaps c c, which may either be sewed on or cut out of one piece with the remainder of the upper. In order to last the upper, I place the same upon a last. Then I put the insole C upon the last and secure on this insole the shank-spring A by means of tacks d, driven through 35 the holes a in the spring. I then draw the edge of the upper over the edge of the insole and secure the same by tacks in the usual manner, with the exception of the shank-flaps c c, which 40 are drawn inward from opposite sides over the shank-spring A, and then depressed upon the spikes b of said spring, so that they are firmly retained in position. When this has been accomplished, I put on a leather shank,

D, which serves to cover the points of the 45 spikes b, and then apply the outer sole, E, in the manner usually practiced. If the boot is provided with a welt, the outer sole can be sewed on before the last is removed; but if the boot has no welt it must be removed from the 50 last in order to sew on the outer sole by stitches passing through and through. In the example represented by the drawings a welt, F, is secured to the upper and made to extend round the toe part and as far as the 55 shank on both sides of the upper, and the space between the inner edges of said welt is occupied by a felt sole, G. In this case the outer sole, E, can be sewed to the welt as far as the same extends without removing the upper from the last; but in order to sew the remaining portion of the outer sole to the upper 60 the last must be removed.

The principal advantage of my invention is due to the spikes b of shank-spring A and to 65 the shank-flaps c c of the upper. By drawing the shank-flaps over the spikes b, the shank portion of the upper is firmly retained in position, and it is not liable to be thrown out of shape during the operation of securing the 70 outer sole to the upper.

What I claim as new, and desire to secure by Letters Patent, is—

1. As an improved article of manufacture, the shank-spring provided with projecting 75 spikes, substantially as described.

2. The combination, with the inner sole, C, of a shank-spring, A, having spikes b, and an upper, B, having shank-flaps c c, substantially as described.

In testimony whereof I have hereunto set my hand and seal in the presence of two subscribing witnesses.

MORRIS WISE. [L. S.]

Correction in Letters Patent No. 366,142.

It is hereby certified that the name of one of the assignees in Letters Patent No. 366,142, granted July 5, 1887, upon the application of Morris Wise, of New York, New York, for an improvement in the "Manufacture of Boots or Shoes" was erroneously written and printed "E. F. Fellows," whereas said name should have been written and printed *E. F. Fellowes*; and that the said Letters Patent should be read with this correction therein that the same may conform to the record of the case in the Patent Office.

Signed, countersigned, and sealed this 19th day of July, A. D. 1887.

[SEAL.]

D. L. HAWKINS,

Acting Secretary of the Interior.

Countersigned:

BENTON J. HALL,

Commissioner of Patents.
